CLOSURE FOR RADIATOR NECKS AND
THE LIKE

Michael B. Andrie, Grand Rapids, Mich., assignor to W. B. Jarvis Company, Grand Rapids, Mich.

Application April 15, 1929. Serial No. 355,104

12 Claims. (Cl. 220—40)

The main objects of this invention are:

First, to provide a closure for radiator necks, oil tanks and the like which may be very quickly applied or removed, the opening being very effectively sealed.

Second, to provide a structure having these advantages in which the parts are simple and economical in structure and very strong and durable.

Objects pertaining to details and economies of my invention will definitely appear from the description to follow. The invention is defined in the claims.

A structure which embodies the features of my invention is clearly illustrated in the accompanying drawings, in which:

Fig. 1 is a vertical central section of a radiator closure embodying the features of my invention taken on a line corresponding to line 1—1 of Figs. 2, 4 and 6.

Fig. 2 is a fragmentary view partially in section on line 2—2 of Fig. 1.

Fig. 3 is an inverted view of the cap proper.

Fig. 4 is a plan view of the closure neck.

Fig. 5 is a fragmentary vertical central section through the neck, the section lines corresponding to that of Fig. 1.

Fig. 6 is a horizontal section on line 6—6 of Fig. 1.

Fig. 7 is an inverted view of the spring closure disk and thrust member.

In the accompanying drawings, the embodiment illustrated is such as I employ for radiator closures and the like. It will be understood that my improvements have very wide adaptation, but this disclosure will enable such adaptation as may be desired.

The neck 1 is provided with an inturned annular flange 2 constituting a gasket seat. On the inner edge of this flange I form two or more downwardly diverging or tapered socket or coupling members 3. These coupling members 3 are in the form of flange-like projections on the inner edge of the flange 2 and are provided with stops 4 at corresponding ends thereof.

The cap 5 is chambered and its flange 6 is of substantially greater diameter than the neck. The cap has a depending central shank 19 provided with lugs 7. The combined closure disk and thrust member 8 is seated on the end of the shank, it being provided with a slot 9 engaging the lugs so that the disk is held against rotation. The coupling member 10 is seated on the shank over the disk 8 also in engagement with these lugs 7.

The clamping screw 11 is threaded into the shank, a washer 12 being provided to overlap the

coupling member. The coupling member is shouldered at 13 and is provided with downwardly flaring segmental male joint or socket engaging members 14 adapted to be engaged and disengaged with the socket members by relative rotative movement of the neck and cap. The engaging movement tends not only to engage the parts but to exert a downward pull on the cap.

In the embodiment illustrated the socket engaging members 14 are formed as a part of a continuous flange which permits the coupling member being formed as a sheet metal stamping. The portions 15 of the flange constitute supporting or reinforcing members and also stop engaging parts as shown in Fig. 6. A gasket or packing 16 is clamped between the shoulder 11 and the member 8 so that it is effectively secured to the cap with portions projecting to engage the seat on the neck.

This seat is preferably provided with an annular bead 17 and the thrust member 8 is also preferably provided with an annular bead 18 disposed in opposed relation to the bead 17 so that the gasket has a very effective sealing engagement with these parts. The member 8 constitutes a thrust spring and closure member and, in effect, is provided with a yielding facing engaging the gasket seat on the neck.

Closures embodying my improvements may be very easily engaged and disengaged and the rotative movement of the cap draws the gasket firmly upon the neck seat. The spring yields to permit this and also provides a tensioning means for holding the parts in their adjusted positions. That is, the member 8 applies yielding pressure to the co-engaging parts so that the cap will not become accidentally disengaged.

My improvements are well adapted for closures for radiators and the like, the cap lying close to the neck.

Having thus described my invention what I claim as new and desire to secure by Letters Patent is:

1. In a closure, the combination of a neck having an inturned annular flange provided with opposed segmental downwardly diverging socket coupling members depending from its edge, said socket members having stops at corresponding ends thereof, a cap having a central depending shank provided with projecting lugs, a disk-like spring thrust member seated on said shank in engagement with said lugs, a shouldered coupling member seated on said closure disk in engagement with said lugs on said shank, said coupling member being provided with downwardly

- projecting opposed segmental outwardly flaring socket engaging members engageable and disengageable with said socket members by a relative rotative movement, a screw threaded into said shank to secure said thrust and coupling members thereto, and an annular gasket disposed between said thrust member and the shoulder portion of said coupling member with its inner portion clamped thereby and its outer portion coating with the flange of said neck which constitutes a gasket seat. 80
2. In a closure, the combination of a neck having an inturned annular flange provided with opposed segmental downwardly diverging socket members having stops at corresponding ends thereof, a cap having a central depending shank provided with projecting lugs, a disk-like spring thrust member seated on said shank in engagement with said lugs, a shouldered coupling member seated on said closure disk in engagement with said lugs on said shank, said coupling members being provided with downwardly projecting opposed segmental outwardly flaring socket engaging members engageable and disengageable with said socket members by a relative rotative movement, a screw threaded into said shank to secure said thrust and coupling members thereto, and an annular gasket disposed between said thrust and the shoulder portion of said coupling member with its inner portion clamped thereby and its outer portion coating with the flange of said neck which constitutes a gasket seat, said flange and said thrust member being provided with opposed annular gasket engaging beads. 90
3. In a closure, the combination of a neck provided with an annular flange constituting a gasket seat with segmental diverging socket members, a cap having a depending central support, a spring thrust member mounted on said support, a coupling member mounted on said support, said coupling member being provided with segmental diverging socket engaging members engageable and disengageable with said socket members by relative rotative movement, and a gasket clamped between said thrust member and said coupling member whereby it is yieldingly supported by said thrust member in coacting relation to said gasket seat. 100
4. In a closure, the combination of a neck provided with an annular gasket seat and having segmental diverging socket members at the inner side of said seat, a cap, a coupling member mounted within said cap and having segmental flaring male coupling members engageable and disengageable with said socket members by a relative rotative movement, a closure member supported at its inner edge within said cap with its outer edge in overlying relation to said gasket seat on said neck, and a gasket carried by said cap and yieldingly supported by said spring member to coact with said gasket seat on said neck, said spring member and gasket seat being provided with opposed annular beads. 110
5. In a closure, the combination of a neck having an annular flange provided with opposed segmental diverging joint members depending from its edge, said joint members having stops at corresponding ends, a cap having a central depending shank and provided with opposed segmental tapered joint members engageable and disengageable with said joint members of said neck by a rotative movement, a disk-like spring closure member seated on said shank with its outer edge overhanging said neck, and a gasket member supported below said disk to coact with 120
- said neck, said flange and closure member being provided with opposed annular ribs. 130
6. In a closure, the combination of a neck provided with an annular gasket seat and having diverging socket members at the inner side of said seat, a cap, a coupling member mounted within said cap and having flaring male coupling members engageable and disengageable with said socket members by a relative rotative movement, a spring closure member supported at its inner edge within said cap with its outer edge in overlying relation to said gasket seat on said neck, and a gasket carried by said cap and yieldingly supported by said spring member to coact with said gasket seat on said neck, said gasket seat and closure member having opposed annular ribs 140
- engaging said gasket. 150
7. In a closure, the combination of a neck provided with diverging socket members, a cap provided with opposed diverging socket engaging members engageable and disengageable with said socket members by a relative rotative movement, said socket members being provided with stops at corresponding ends thereof, a spring thrust member carried by said cap, and a gasket interposed between said spring thrust member and the neck, said gasket seat having an annular rib engaging said gasket. 160
8. In a closure, the combination of a neck provided with tapered coupling members, a cap provided with coacting tapered coupling members engageable and disengageable with said coupling members of said neck by a rotative movement, a spring closure member arranged within said cap in opposed relation to said neck and acting to apply spring tension to said joint members when they are in engagement, and a gasket carried by said cap, said gasket seat having an annular rib engaging said gasket. 170
9. In a closure, the combination of a neck provided with segmental diverging socket members, a cap provided with opposed segmental diverging socket engaging members engageable and disengageable with said socket members by a relative rotative movement, a spring thrust member carried by said cap, and a gasket interposed between said spring thrust member and the neck, said gasket seat having an annular rib engaging said gasket. 180
10. In a closure, the combination of a neck provided with joint members in the form of conical segments, a cap provided with coacting joint members in the form of conical segments, and a spring carried by said cap and acting to apply spring tension to said joint members when in engagement. 190
11. In a closure, the combination of a neck provided with tapered joint members, a cap provided with coacting tapered joint members engageable and disengageable with said joint members of said neck by a rotative movement, a spring closure member arranged within said cap in opposed relation to said neck and acting to apply spring tension to said joint members when they are in engagement, and a gasket carried by said cap, said gasket seat having an annular rib engaging said gasket. 200
12. In a closure, the combination of a neck provided with segmental diverging socket members, a cap provided with opposed segmental diverging socket engaging members engageable and disengageable with said socket members by a relative rotative movement, and a spring thrust member carried by said cap. 210
